J. S. COSDEN & J. W. COAST, JR.
ART OF CRACKING PETROLEUM HYDROCARBONS.
APPLICATION FILED DEC. 26, 1916.

1,261,215.

Patented Apr. 2, 1918.

UNITED STATES PATENT OFFICE.

JOSHUA S. COSDEN AND JOHN W. COAST, JR., OF TULSA, OKLAHOMA, ASSIGNEES, BY DIRECT AND MESNE ASSIGNMENTS, TO THE PROCESS COMPANY, A CORPORATION OF MARYLAND.

ART OF CRACKING PETROLEUM HYDROCARBONS.

1,261,215.

Specification of Letters Patent. Patented Apr. 2, 1918.

Application filed December 26, 1916. Serial No. 138,996.

To all whom it may concern:

Be it known that we, JOSHUA S. COSDEN and JOHN W. COAST, Jr., citizens of the United States of America, residents of 5 Tulsa, in the county of Tulsa, State of Oklahoma, have invented certain new and useful Improvements in the Art of Cracking Petroleum Hydrocarbons, of which the following is a full, clear, and exact description, 10 reference being had to the accompanying drawing, forming a part of this specification.

Our invention relates to improvements in the art of cracking high boiling petroleum hydrocarbons to obtain a cracked product 15 adapted for use as a motor spirit. The product eventually obtained is known as cracked gasolene, or a substitute for gasolene. One of the objects of the invention 20 is to provide an economical method of producing a highly desirable low boiling product of this kind.

More specifically stated, an object of the invention is to utilize the hot vapors resulting from one cracking operation to heat and crank another hydrocarbon fluid. To accomplish this, the vapors flowing from a 25 primary cracking chamber are preferably superheated and introduced into a supplemental cracking chamber, and a finely divided hydrocarbon fluid is then forced into the superheated vapors. As a consequence, the finely divided hydrocarbon fluid is 30 cracked and, being relatively cool, it also serves as a primary condenser for the previously vaporized high boiling hydrocarbons. The high boiling condensate resulting from this operation is preferably conducted back to the primary cracking chamber.

Another object is to increase the yield and improve the product by introducing natural gas into the hot vapors passing from the primary cracking chamber, and with this 45 object in view, we preferably use the natural gas in superheating the vapors flowing from the primary cracking chamber. The natural gas may be heated to a very high temperature, for example 900° F., and then

forced into the hot vapors, thereby super- 50 heating the vapors to such a degree that the hot fluid may be used as the heating medium for the second cracking operation.

The natural gas is forced into the hot vapors at a point where the vapors are confined under a high pressure, preferably 55 greater than 50 pounds per square inch, and it is evident that the hot gas unites with, or is absorbed by the hot petroleum hydrocarbon vapors in such a manner as to 60 materially increase the yield, at the same time beneficially altering the properties of 65 the hydrocarbon fluid. Before reaching the main condenser, the hot mixture is preferably conducted, under pressure, through a steam chamber where it commingles with a spray of relatively cool steam. This causes 70 some of the high boiling hydrocarbons to condense, and the properties of the product are further improved by the action of the 75 steam. We are unable at this time to accurately explain the precise action which 80 takes place when the steam is introduced into the compressed hydrocarbon mixture, but it appears that some of the constituents 85 of the steam unite with the hydrocarbons so as to form part of the low boiling product. The steam also eliminates a large percentage of the carbon and other objectionable elements that are usually removed by treating the product with sulfuric acid.

The ordinary well known method of cracking petroleum hydrocarbons consists in subjecting the hydrocarbons, while under pressure, to a high degree of heat, thereafter conducting the vapors to a primary reflux condenser where the relatively heavy hydrocarbons are condensed and prevented from passing to the main condenser. The ordinary primary condenser also has the important function of lowering the temperature of the light hydrocarbon vapors before they reach the main condenser. All 90 of these functions are performed by the supplemental cracking chamber and steam chambers to which we have previously referred, the elements associated with these 95 chambers serving to economize in the use

of fuel, to very materially improve the product, to increase the yield, and also to condense the high boiling hydrocarbons.

To set forth a preferred form of the invention, we have herein described a specific combination of elements and a method including a precise combination of steps which follow each other in a particular sequence, but it is to be understood that the invention comprehends modifications and variations within the scope of the claims hereunto appended.

The drawing is a diagrammatical view of an apparatus adapted for use in carrying out the new method.

To illustrate the invention we have shown a retort or primary cracking chamber 1 arranged over a heating chamber 2, a vapor pipe 3 leading from the primary cracking chamber 1 to a supplemental cracking chamber 4, a vapor pipe 5 connecting the upper portion of said supplemental cracking chamber to a steam chamber 6, a vapor pipe 7 connecting the upper portion of steam chamber 6 to the lower portion of a steam chamber 8, a vapor pipe 9 leading from the upper portion of steam chamber 8 to a main condenser 10, and a pipe 11 for conducting the low boiling condensate from condenser 10 to a tank 12.

A discharge member 13, arranged in the upper portion of the supplemental cracking chamber 4, is adapted to discharge a finely divided liquid hydrocarbon into the hot vapors. A pump 14 may be operated to force a high boiling hydrocarbon liquid, through a conductor 15, to the discharge member 13. 16 designates a regulating valve in the conductor 15.

40 A main steam pipe 17 is provided with branches 18 and 19 for conducting steam into the steam chambers 6 and 8 respectively. Each of the branch pipes 18 and 19 has a discharge member 20 at its lower end, adapted to discharge a spray of steam into the vapors. Regulating valves 21 may be adjusted to regulate the flow of steam to the steam chambers.

Natural gas passing from a gas compressor 22, is preferably forced through a superheater 23 and thence into a pipe 24 leading to the insulated vapor pipe 3. 24' designates a regulating valve in the gas pipe 24.

The condensate forming in the chambers 4, 6 and 8 may be returned to the main cracking chamber 1, or it may be conducted to a cooling coil 25 having a discharge pipe 26 for conducting the liquid to a tank 27. Discharge pipes 28 extending downwardly from the bottoms of the chambers 4, 6 and 8 are connected to branch pipe 29 adapted to communicate with a return pipe 30 which leads to the main cracking chamber 1. These branch pipes 29 are

also adapted to communicate with a pipe 31 connected to the cooling coil 25. Valves 32 may be opened to place the branch pipes in communication with the return pipe 30, or if desired the valves 32 may be closed and the valves 33 opened to allow the condensate to flow to the cooling coil 25.

A pressure regulating valve 34 in the vapor pipe 9 may be adjusted to maintain any desired pressure in the steam chambers 8 and 6, supplemental cracking chamber 4 and main cracking chamber 1. A regulating valve 35, in the pipe 31, is also adjusted to maintain the desired pressure when the condensate is permitted to flow to the coil 25.

Although we have shown and described a specific structure adapted for use in following our method, it is to be understood that the illustration is merely diagrammatical, and that any suitable apparatus may be used in carrying out the method herein claimed.

The new method may be used in cracking various high boiling hydrocarbon products resulting from the distillation of crude petroleum, and is particularly adapted for use in cracking inexpensive heavy hydrocarbons having a boiling point of about 450° F. to 700° F. The substances to be treated may be introduced into the main cracking chamber 1 in any suitable manner, and the valve 34 located beyond the steam chamber 8 may be adjusted to maintain the desired high pressure in the steam chambers and cracking chambers. This pressure is greater than 50 pounds per square inch, preferably about 75 to 80 pounds per square inch.

To more clearly explain the invention, the approximate temperatures at various parts of the apparatus have been marked on the drawings, but it is to be clearly understood that these figures are not essentially accurate, the main object being to show that the temperature of the vapors is increased and decreased at different points in the apparatus.

The vapors flowing in the vapor pipe are superheated by the natural gas flowing from the heater 23 to said vapor pipe, and the hot mixture is then conducted into the supplemental cracking chamber 4. The natural gas under pressure and at a high temperature, for example, 900° F., commingles with the confined vapors, so as to increase the yield, at the same time increasing the temperature of the vapors to such a degree (for example 800° F.) that the mixture serves as a heating medium for cracking the high boiling hydrocarbon fluid passing from the discharge member 13 in the supplemental cracking chamber. The finely divided fluid discharged into this chamber is preferably a high boiling product resulting from the distillation of crude petroleum. If desired, it may be preheated, but it is preferably in

a liquid state and at about the temperature of the atmosphere. This high boiling fluid is vaporized and cracked while confined under pressure in the supplemental cracking chamber, and being relatively cool, it serves as means for condensing previously vaporized high boiling fractions.

Another advantage is the elimination of coke or carbon by the action of the relatively cool liquid in the supplemental cracking chamber. A large percentage of the carbon or coke carried by the vapors, drops into a trap formed at the bottom of the supplemental cracking chamber, and the high boiling condensate overflowing into the discharge pipe 28 is preferably conducted back to the primary cracking chamber.

The hot fluid passing from the upper portion of the supplemental cracking chamber 10 is conducted into the steam chamber 6 where it is acted upon by a spray of relatively cool steam which commingles with the mixture of natural gas and hydrocarbon vapors. The saturated steam is superheated by the hot fluid in the steam chamber 6 and the new mixture passes out through the vapor pipe 7 and into the steam chamber 8 where it is subjected to a second treatment by a spray of relatively cool steam. To obtain the most desirable results, we preferably use two or more steam chambers, and it will be observed that such chambers serve as condensers for "knocking back" the high boiling hydrocarbons. Since the supplemental cracking chamber and steam chambers constitute a series of reflux condensers, the high boiling liquid may be vaporized very rapidly in the main cracking chamber 1. The heavy hydrocarbons carried from the main cracking chamber will 40 be condensed in the reflux condensers, and the desired low boiling hydrocarbons will pass through the pressure regulating valve 34 to the main condenser 10. The contents of this condenser are preferably maintained under the normal atmospheric pressure.

The apparatus herein shown is claimed in an application for patent filed by us Dec. 26, 1916, Serial Number 138,997.

We claim:—

50 1. In the art of treating high boiling petroleum hydrocarbons to obtain a substitute for gasoline, the method which comprises cracking and vaporizing such hydrocarbons, heating a fluid to a temperature higher than the temperature of the hydrocarbon vapors, mixing said fluid with said vapors so as to superheat the vapors, introducing a relatively cool hydrocarbon fluid into the hot mixture, thereby cracking said hydrocarbon fluid, and conducting vapors from the last mentioned fluid to a condenser.

2. In the art of treating high boiling petroleum hydrocarbons to obtain a substitute for gasoline, the method which comprises

cracking and vaporizing such hydrocarbons, introducing gas into the hot vapors, introducing a relatively cool hydrocarbon fluid into the hot mixture, thereby cracking said hydrocarbon fluid, and conducting vapors from the last mentioned fluid to a condenser. 70

3. In the art of treating high boiling petroleum hydrocarbons to obtain a substitute for gasoline, the method which comprises cracking and vaporizing such hydrocarbons, confining the vapors under a pressure greater than 50 pounds per square inch, heating natural gas to a temperature higher than the confined vapors, forcing the hot natural gas into the confined vapors so as to superheat the vapors, forcing a relatively cool high 80 boiling hydrocarbon fluid into the hot mixture, thereby cracking the last mentioned hydrocarbon fluid, and conducting the vapors to a condenser.

4. In the art of treating high boiling hydrocarbons to obtain a substitute for gasoline, the method which comprises cracking such hydrocarbons, introducing a relatively cool hydrocarbon fluid into the hot vapors resulting from the cracking operation, thereby cracking said hydrocarbon fluid, conducting the vapors from said hydrocarbon fluid, then introducing steam into the vapors, and conducting the resultant mixture of steam and hydrocarbon vapors to a condenser. 95

5. In the art of treating high boiling hydrocarbons to obtain a substitute for gasoline, the method which comprises cracking such hydrocarbons, confining the resultant vapors under a pressure greater than 50 pounds per square inch, forcing a finely divided and relatively cool hydrocarbon fluid into the confined vapors, thereby cracking said hydrocarbon fluid, thereafter introducing steam into the vapors flowing from said hydrocarbon fluid while said vapors are confined under pressure, and conducting the mixture of steam and hydrocarbon vapors to a condenser. 100

6. In the art of treating high boiling petroleum hydrocarbons to obtain a substitute for gasoline, the method which comprises cracking such hydrocarbons in a primary cracking chamber, introducing a relatively hot fluid into the resultant vapors so as to 115 superheat said vapors, forcing the hot mixture into a supplemental cracking chamber, at the same time forcing a relatively cool hydrocarbon fluid into the hot mixture, conducting vapors from said supplemental 120 cracking chamber, then introducing steam into said vapors, and conducting the steam and hydrocarbon vapors to a condenser.

7. In the art of treating high boiling petroleum hydrocarbons to obtain a substitute for gasoline, the method which comprises cracking such hydrocarbons in a primary cracking chamber, introducing a relatively 125

4
hot fluid into the resultant vapors so as to superheat said vapors, forcing the hot mixture into a supplemental cracking chamber, at the same time forcing a relatively cool 5 hydrocarbon fluid into the hot mixture, conducting vapors from said supplemental cracking chamber, then introducing steam

into said vapors, conducting the steam and hydrocarbon vapors to a condenser, and returning condensate from said supplemental 10 cracking chamber to said primary cracking chamber.

JOSHUA S. COSDEN.
